PHILO B. TINGLEY, OF NEW YORK, N. Y.

MICROMETER LINE-SPACING ADJUSTMENT FOR WRITING-MACHINES.

1,381,143.

Specification of Letters Patent. Patented June 14, 1921.

Application filed February 2, 1920. Serial No. 355,884.

To all whom it may concern:

Be it known that I, PHILO B. TINGLEY, a citizen of the United States, residing at 234 W. 104th street, New York, county of 5 New York, State of New York, have invented an Improvement in Micrometer Line-Spacing Adjustments for Writing-Machines, of which the following is a specification.

10 In writing machines as ordinarily constructed, there are three regular spacings provided. Heretofore, adjustable line spacing attachments, known as variable spacing mechanism, have been applied to writing 15 machines to adapt them to space irregularly when such irregular spacing may be desirable.

This invention has for its object to provide a novel micrometer line spacing adjustment for such variable spacing mechanism.

In the accompanying drawing forming a part of this specification, I have shown the novel micrometer line spacing adjustment in connection with variable spacing mechanism which may be applied to writing machines of any make, either old or new.

Figure 1 is a plan view of variable spacing mechanism equipped with my novel micrometer adjustment, showing so much of a writing machine as is necessary to illustrate the invention;

Fig. 2 a sectional view on line 2—2 in Fig. 1, looking in the direction of the arrows;

Fig. 3 an elevation of variable spacing mechanism as seen from the opposite side of Fig. 2, and equipped with my novel 40 micrometer adjustment, showing the spacing mechanism in its gripping position on the clutch drum;

Fig. 4 a sectional view on line 4—4 in Fig. 2, showing the scroll wheel in releasing position with respect to the toothed slide of the spacing mechanism;

Fig. 5 a perspective view of the scroll wheel;

Fig. 6 an elevation corresponding with Fig. 3, but disclosing a modified form of scroll wheel, and showing the spacing mechanism in its releasing position on the clutch drum; and

Fig. 7 is a fragmentary end elevation of 55 the structure of Fig. 6.

20 denotes the frame of any writing ma-

chine, 21 the platen, 22 the shaft therefor, 23 the handle and 24 the ratchet wheel on said shaft.

A clutch drum 25 is mounted on the shaft 60 to turn therewith, and on this drum is a clutch band which consists of an upper clutch member 26, a lower clutch member 27, and a link 28. The upper and lower clutch members are hinged together 65 as indicated at 29, and the lower end of the link is hinged to the lower clutch member as indicated at 30. There is an eccentric opening 31 in the upper end of the link and in this opening is loosely fitted a 70 perforated eccentric hub 32 having an operating lever 33. A screw 34 passing through the perforation in the eccentric hub, through the eccentric opening, and through the upper clutch member, connects these parts together. By referring to Fig. 2 it will be seen that when the operating lever of the hub is thrown from left to right, shoulder 35 on the hub will engage shoulder 36 of the opening and force the link to travel a 75 short distance upwardly, thus drawing the lower clutch member into gripping relation with respect to the clutch drum. 37 denotes a lug on the operating lever which is adapted to engage the link when the clutch 80 band is in its releasing position on the clutch drum.

38 denotes the spacing lever of the machine, 39 a block arranged in the frame for sliding movement, and 40 a pin extending 90 from the block and which is adapted to be engaged by the spacing lever, as is plainly disclosed in Figs. 1 and 2. The block is also provided with a boss 41 to which one end of a lever 42 is pivotally attached by 95 means of a screw 43. The other end of this last mentioned lever is pivoted to the operating lever, as indicated at 44. A pin 45 extending downwardly from boss 41 has attached to it one end of a spring 46 the 100 other end of which is attached to the frame of the machine. This spring normally holds the parts of the mechanism in the position shown in Figs. 1 and 2.

As is more clearly shown in Fig. 3, the 105 upper clutch member is provided with an arc shape groove 72 and in this groove is arranged a toothed slide 47. A scroll wheel 48 is also secured to the upper clutch member, the latter being cut away as indicated 110 at 73 so that the scroll 74 of the scroll wheel may engage the teeth 75 on the slide. At

49 is indicated a stop pin carried by the frame and so arranged that end 50 of the toothed slide may engage it. An extension 51 on the upper clutch member engages the 5 stop pin when the clutch band is in its releasing position on the clutch drum and the spacing mechanism is held in the position shown in Figs. 1 and 2.

It will be apparent that when the spacing 10 lever is thrown in the direction indicated by the arrow in Fig. 1, the operating lever of the eccentric hub will immediately be thrown so that the clutch band will grip the clutch drum and rotate the platen. As soon as the 15 end of the toothed slide strikes the stop pin, the rotation of the platen will cease. Hence, by adjusting the toothed slide in the upper clutch member, any desired spacing may be obtained.

20 Two forms of scroll wheel are disclosed. That of Figs. 1 to 5 has its scroll arranged in a plane which is tangent to the toothed slide, and that of Figs. 6 and 7 has its scroll arranged in a vertical plane which is trans- 25 verse with respect to the slide. The scroll wheel of Figs. 1 to 5 is arranged to oscillate on a vertical expansion stud 52 having a base 53 which passes to a point beyond the scroll and thus assists in balancing the wheel. 30 Integral with or attached to the base is a pivot block 54 which is attached to the upper clutch member by means of a pin 55 passing through lugs 56 and 57 extending from the pivot block and the upper clutch member, re- 35 spectively. A spring 58 normally holds the scroll wheel so that its scroll engages the teeth of the toothed slide, as shown in Fig. 3. A cap screw 59 engages the expansion stud and holds the scroll wheel thereon, and is 40 adapted to lock the scroll wheel in any of its adjusted positions. The modified scroll wheel of Figs. 6 and 7 is arranged to oscillate on a horizontally arranged screw 60 which is embedded in a pivot block 61. A pin 62 45 passing through the upper clutch member and through extensions 63 on the block, pivots the block to the member. A flat spring 64 secured to the upper clutch mem- 50 ber normally holds the scroll in the position indicated in Fig. 6.

In each instance the scroll wheel is graduated as indicated at 65, the graduation accurately denoting the distance which the scroll forces the toothed slide to travel as 55 the wheel is rotated. An indicating pointer 66 is provided for each graduation. A scale 67 on the outer periphery of the upper clutch member corresponds with the ordinary spacings of any writing machine. An indicating pointer 68 for scale 67 is attached to the toothed slide, as shown. A finger piece 69 is secured to the toothed slide.

When it is desired to set the toothed slide to make a regular spacing as indicated by 65 the scale on the upper clutch member, the

scroll wheel, in each instance, may be thrown on its pivot so that the scroll releases the toothed slide. It will be apparent that the slide may then be manipulated by the finger piece thereon. After the adjustment of the 70 slide, the graduated scroll may be returned to its normal position and then rotated more or less until the scroll contacts between the teeth of the slide and thereby holds the slide in position. When it is desired to set the 75 toothed slide to make an irregular spacing, all that is necessary is to rotate the scroll wheel the proper distance indicated by the graduation thereon, as will be readily understood. The toothed slide may be set to make 80 any desired regular spacing and then the micrometer adjustment may be brought into action to obtain a spacing greater or less than that regular spacing, or all of the 85 adjustments may be made by rotating the scroll wheel. It will be apparent that the micrometer adjustment of the present invention affords a very accurate means for obtaining irregular spacings of any desired 90 magnitude.

In using the variable spacer shown and described, it is necessary that the ratchet wheel be free from the spring pressed roller 70 of the machine, or that it be free from the shaft. I have shown mechanism, indicated 95 generally by 71, similar to that of my Patent No. 1,312,063, granted August 5, 1919, for causing the ratchet wheel to grip the shaft or to be released therefrom. It may be observed that this mechanism forms no part of 100 the present invention. In using the spacer, the mechanism referred to is in its releasing position with respect to the shaft. However, when it is desired to turn from a line which is being written upon, the mechanism is operated so that the ratchet wheel is forced to 105 turn with the shaft. When now it is desired to return to the writing line, this may be accurately done by engaging the same notch in the ratchet wheel with the roller as was be- 110 fore engaged.

What I claim is:

1. A micrometer line spacing adjustment for writing machines comprising a platen, a shaft therefor, a spacing device thereon, 115 clamping means uniting the shaft and spacing device, a spacing lever, means for setting the spacing device for a regular space or a multiple thereof and a scroll wheel thereon for altering said regular space 120 after setting and capable of setting an irregular space in said setting device.

2. A micrometer line spacing adjustment for writing machines comprising a platen, a shaft therefor, a spacing device thereon, 125 clamping means uniting the shaft and the spacing device, a spacing lever, and means for setting the spacing device and locking it at a regular spacing interval and at an irregular spacing interval. 130

3. A micrometer line spacing adjustment for writing machines comprising a space controlling member, a scale therefor carrying indications of settings for full line spacing and a plurality thereof, a graduated scroll wheel member having a portion contacting said space controlling member and at times acting as a lock for said space controlling member and at other times as an actuator therefor.

4. A micrometer line spacing adjustment for writing machines comprising a sliding space regulating member, means for retaining said member in locked position so as to hold the space regulating member in full line spacing position, and means to move the locking means so as to produce other than full line spacing.

5. A micrometer line spacing adjustment for writing machines, comprising a graduated scroll wheel pivotally attached to the spacing mechanism of the machine and co-operating with a toothed slide for varying the magnitude of the spacings of said spacing mechanism, said scroll wheel being adapted to swing on its pivot to release said toothed slide.

6. A micrometer line spacing adjustment for writing machines, comprising a graduated scroll wheel pivotally attached to a part of the machine and co-operating with a toothed slide for varying the magnitude of the spacings of the spacing mechanism of said machine, said scroll wheel being adapted to swing on its pivot to release said toothed slide.

7. A micrometer line spacing adjustment for writing machines comprising a space regulating member, a scale therefor, means for locking said member in correspondence with said scale, means for moving said locking means from locking position, a graduated scale therewith, and means for indicating the movements of the locking means.

8. A micrometer line spacing adjustment for writing machines, comprising a graduated scroll wheel pivotally attached to a part of the machine and co-operating with a toothed slide for varying the magnitude of the spacings of the spacing mechanism of

said machine, said scroll wheel being adapted to swing on its pivot to release said toothed slide, and said toothed slide carrying means for adjusting it independently of said scroll wheel.

55

9. A micrometer line spacing adjustment for writing machines, comprising a graduated scroll wheel pivotally attached to the spacing mechanism of the machine and co-operating with a toothed slide for varying the magnitude of the spacings of said spacing mechanism, said scroll wheel being adapted to swing on its pivot to release said toothed slide, and said toothed slide carrying means for adjusting it independently of said scroll wheel.

60

10. A micrometer line spacing adjustment for writing machines, comprising a graduated scroll wheel and a toother slide co-operating therewith, said slide arranged in an arc shape groove in the spacing mechanism of said machine and adapted to be engaged by the scroll of said scroll wheel, and said scroll wheel being pivoted to said spacing mechanism and adapted to be swung on its pivot to release said scroll from said toothed slide, whereby said toothed slide may be adjusted independently of said scroll wheel.

70

11. A micrometer line spacing adjustment for writing machines, comprising a space regulating member, a scale therefor, means for locking said member in correspondence with said scale, means for moving said locking means from locking position, a graduated scale therewith, means for indicating the movement of the locking means and means for shifting the locking means out of locking position.

75

12. A micrometer line spacing adjustment for writing machines comprising a space controlling member, a scale therefor carrying indications of settings of said control member, a graduated scroll wheel, a scale therefor, means for indicating the position of the scroll wheel, and means for moving said space control member so that its settings are indicated on the second scale.

85

In testimony whereof I affix my signature.

PHILO B. TINGLEY.
